[57] CLAIM

The ornamental design for a holder for paper towel roll,
as shown and described.

DESCRIPTION

FIG. 1 is a front view of a holder for paper towel roll in
accordance with my new design;

FIG. 2 is a side view as seen from the right side of FIG.
1 thereof, the opposite side being a mirror image
thereof;

FIG. 3 is a top view thereof;

FIG. 4 is a bottom view thereof; and

FIG. 5 is a rear view thereof.
